Hazard and Miller

UNITED STATES PATENT OFFICE.

JAMES MARTIN WATTS, OF LOS ANGELES, CALIFORNIA.

SPARK-PLUG.

1,255,252.

Specification of Letters Patent. Patented Feb. 5, 1918.

Application filed August 13, 1917. Serial No. 185,924.

To all whom it may concern:

Be it known that I, JAMES MARTIN WATTS, a citizen of the United States, residing at Los Angeles, in the county of Los Angeles and State of California, have invented new and useful Improvements in Spark-Plugs, of which the following is a specification.

This invention relates to a spark plug for internal combustion engines.

10 It is the principal object of this invention to provide a spark plug which may be readily assembled or dismantled, and which is designed with electrodes not liable to become corroded or short-circuited by carbon deposits.

Other objects will appear hereinafter.

The invention is illustrated, by way of example, in the accompanying drawings in which:

20 Fig. 1 is a view in side elevation illustrating the spark plug with which the present invention is concerned, with parts broken away to more clearly disclose the elements of which it is composed.

25 Fig. 2 is a view in plan as viewed from the lower end of the plug, particularly disclosing the circular formation of the central electrode and the annular spark gap.

30 Fig. 3 is a view in perspective illustrating the central electrode as disassociated from the other parts of the plug and further disclosing the fragmentary portion of the surrounding electrode.

35 Referring more particularly to the drawings, 10 indicates the metallic body portion of a spark plug which is formed with a tubular lower extension 11 externally threaded to be mounted within a bore in the end wall 12 of an engine cylinder. An enlarged 40 flange portion 13 is formed around the body of the plug and is adapted to bear upon the boss through which it is screwed. The top 45 of the plug is hexagonal to facilitate in mounting it in position. A metallic packing washer is interposed between the flange and the cylinder head. The lower tubular portion 11 of the plug communicates with a bore 14 of reduced diameter substantially midway the length thereof. This bore, in 50 turn, communicates with an upper bore 15 which is partially threaded adjacent the upper end of the plug to receive a packing nut 16. A porcelain post 17 extends downwardly through the center of the nut 16 55 and has a reduced end portion which passes through the bore 14, the lower end terminat-

ing within the lower tubular body of the plug. A metallic gasket 18 is interposed between the end of the nut 16 and a shoulder upon the porcelain post, and a similar gasket 60 is placed between the shoulder on the post and the shoulder at the bottom of the bore 15, to hold the post in rigid relation to the body of the plug. A bore 19 extends substantially throughout the length of the post 65 to receive the stem 20 of a disk electrode 21. The lower portion of this bore is enlarged to accommodate a shoulder 22 upon the stem 20. The shoulder is held in position by means of a jam nut 23 which is telescoped 70 over the upper end of the porcelain post and engages threads upon the upper extension of the stem. By this means the disk electrode may be rigidly held in position and the electrode and porcelain post separably 75 secured to each other. Suitable washers 24 for locking the jam nut in position are interposed between the nut and the end of the porcelain post, thus holding the nut rigid while a binding post nut 25 is used to clamp 80 the electric wire in position.

As particularly shown in Fig. 1, the members are so arranged and assembled as to cause the disk electrode 21 to be held at a point directly within the tubular body portion 11 of the plug. As this disk is somewhat smaller than the bore within this tubular portion, an annular spark gap 26 will be formed. In this manner a maximum sparking surface will be provided between the 85 electrodes and the danger of mis-fire greatly reduced.

In operation, the apparatus is assembled by first passing the stem of the electrode 21 through the body of the plug, thereafter the porcelain post is placed upon the stem 20 and locked in position by the jam nut 23. The binding nut 25 may then be placed upon the threaded end of the stem. When the packing nut 16 and its washer 18 have been 100 tightened down within the body of the plug, the device is assembled and ready for use.

In operation, a spark will jump from the disk electrode 21 across the annular gap 26 to the circular electrode formed by the body portion 11 of the plug. In case carbon should accumulate, the compression within the engine cylinder will act to loosen it, as the atmosphere and gases are caused to circulate back and forth around the disk and 110 through the annular spark gap 26.

It will thus be seen that the spark plug

here disclosed may be easily assembled and its parts may be removed and replaced when desired, and, furthermore, that with the use of a circular central electrode and an annular spark gap, the maximum spark may be had without danger of corrosion.

While I have shown the preferred form of my spark plug as now known to me, it is evident that various changes in the combination, construction and arrangement of parts may be made by those skilled in the art without departing from the spirit of my invention.

I claim:

- 15 A spark plug comprising a metallic body having an external screw-thread upon its lower end and having a wrench seat upon its upper end and having a bore extending from its lower end to near the center and
 20 having a second reduced bore extending a short distance and having a third bore enlarged relative to the second bore and extending from its upper end and forming a shoulder at its junction with the second bore
 25 and being screw-threaded from the upper end; a packing in the third bore against the

shoulder, a porcelain post having an end extending downwardly and fitting in the second bore and having a shoulder fitting in the third bore against the packing and having 30 a reduced upper end forming a second shoulder and having a longitudinal central bore enlarged at its lower end and forming an internal shoulder, a second packing against the second shoulder, a packing nut around 35 the porcelain post screw-seated in the upper end of the third bore against the second packing, an electrode stem fitting in said central bore and having an enlargement fitting against the shoulder in the central bore 40 and having a screw-threaded upper end, a disk electrode fixed upon the lower end of the stem and fitting loosely in the first bore, a jam nut screw-seated upon the upper end of the stem and chambered to fit upon the 45 upper end of the porcelain post, and a binding post screw-seated upon the upper end of the stem and against the jam nut.

In testimony whereof I have signed my name to this specification.

J. M. WATTS.
